UNITED STATES PATENT OFFICE.

JOSEPH BOMGARDNER, OF WILMOT, OHIO.

DESIGN FOR AN ARTERIAL TUBE.

SPECIFICATION forming part of Design No. 27,171, dated June 8, 1897.

Application filed April 16, 1897. Serial No. 632,519. Term of patent 14 years.

To all whom it may concern:

Be it known that I, JOSEPH BOMGARDNER, a citizen of the United States, residing at Wilmot, in the county of Stark and State of Ohio, 5 have invented and produced a new and original Design for Arterial Tubes, of which the following is a specification, reference being had to the accompanying drawings, forming part thereof.

10 Figure 1 is a side elevation showing my new design. Fig. 2 is a sectional view taken on line x x , Fig. 1.

As shown in the drawings, the leading or material feature of my design consists of a 15 tube provided with tapered portions and a portion of the periphery of said tube milled or provided with grooves or corrugations.

In the accompanying drawings, A represents the tube proper, one end of which is 20 provided with the frustum-shaped portion a . At a short distance from the frustum portion a is located the enlarged spherical portion b , adjacent to which is the cylindrical portion c , upon which cylindrical portion is formed 25 for a short distance thereon the milled or ribbed portion d , said milled or ribbed portion being formed at the end of the cylindrical portion c , as illustrated in the drawings. Adjacent to the milled portion d is the short cylindrical portion d' , adjacent to which is 30 the long tapered portion d'' , which is provided a short distance from its end with the enlarged portion e , which portion is tapered and terminates in a blunt or rounded end f . Intersecting the milled or ribbed portion d are 35 the parallel grooves g , which parallel grooves cross the grooves d at right angles, as illustrated in Fig. 1.

Having described my invention, what I claim as new, and desire to secure by Letters 40 Patent, is—

The design for an arterial tube, as herein shown and described.

In testimony that I claim the above I have hereunto subscribed my name in the presence 45 of two witnesses.

JOSEPH BOMGARDNER.
